US0D1041877S

(12) **United States Design Patent** (10) **Patent No.:** **US D1,041,877 S**
(45) **Date of Patent:** **** Sep. 17, 2024**

(54) **PLAYER CASE**

(71) Applicant: **Jiangxi Hongjiuchang Construction & Installation Engineering Co., Ltd.,**
Jiangxi (CN)

(72) Inventor: **Hong Yu**, Henan (CN)

(*) Notice: Patent file contains an affidavit/declaration under 37 CFR 1.130(b).

(**) Term: **15 Years**

(21) Appl. No.: **29/925,745**

(22) Filed: **Feb. 8, 2024**

(51) **LOC (14) Cl.** **03-01**

(52) **U.S. Cl.**

USPC **D3/218**; D14/410; D14/238.1; D14/217

(58) **Field of Classification Search**

USPC D3/201, 215, 218, 269, 321; D14/440,

D14/217, 238.1

CPC G06F 1/1628; H04B 1/03; H04B 1/3888

See application file for complete search history.

(57) **CLAIM**

The ornamental design for a player case, as shown and described.

DESCRIPTION

FIG. 1 is a perspective view of a player case showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and,

FIG. 8 is bottom plan view thereof.

The broken lines depict portions of the player case and form no part of the claimed design.

1 Claim, 8 Drawing Sheets
